Des. 724

Conrad Harris and
Paul Wm. Joiner of Cincinnati Ohio
Assignors to
A. Bradley, of Pittsburgh, Pa.
Letters Patent No 724. Dated Aug. 28th 1855.

The schedule referred to in these Letters Patent, and making part of the same —

To all whom it may concern:

Be it known that we Conrad Harris, and Paul Wm. Joiner both of Cincinnati, Hamilton County, State of Ohio, have invented or produced a new and Original Design for Wood Burning Stoves; and we do hereby declare the following to be a full and exact description of the same, reference being had to the annexed drawings, and to the letters of reference marked thereon, to wit letter A, showing a perspective view of the stove. What we claim as our invention, and desire to secure by Letters Patent, is the design, configuration, and arrangement of the ornaments on the several parts of the burning stove, as herein represented, and described.
